CLAIM

The ornamental design for a handle cap, as shown and described.

DESCRIPTION

FIG. 1 is a perspective view showing a new design for a handle cap;

FIG. 2 is a front view thereof;

FIG. 3 is a rear view thereof;

FIG. 4 is a right side view thereof, a left side view being a mirror image thereof;

FIG. 5 is a top view thereof; and,

FIG. 6 is a bottom view thereof.

In FIG. 6, the dash-dash broken lines depict features of the handle cap that form no part of the claimed design and the

(Continued)

dash-dot-dash broken lines in the drawing represent the boundaries of the claim and form no part thereof.
